UNITED STATES PATENT OFFICE.

JOHN H. COOK, OF BROOKLYN, NEW YORK, ASSIGNOR TO HENRY B. NEWHALL, OF PLAINFIELD, NEW JERSEY.

DOOR-CLOSING APPARATUS.

SPECIFICATION forming part of Letters Patent No. 679,952, dated August 6, 1901.

Application filed April 19, 1901. Serial No. 56,861. (No model.)

To all whom it may concern:

Be it known that I, JOHN H. COOK, a citizen of the United States, residing in the borough of Brooklyn, city of New York, county of Kings, and State of New York, have invented 5 a new and useful Improvement in Door-Closing Apparatus, of which the following is a specification, reference being had to the drawings accompanying and forming part of the 10 same.

My invention relates to that class of door-closing apparatus more particularly adapted for automatic thermal use, in which a hinged bolt is arranged to project into the path of 15 travel of a door and to keep said door open while the thermal device is intact and to move out of the line of travel of the door and release said door when the thermal devices are weakened or broken. Such devices, how- 20 ever, may be used in connection with other door-closing devices than those operated thermally or automatically.

The particular feature of my invention consists in the arrangement of the parts of such 25 a door-closing apparatus so that the same is reversible and is adapted for use either in a right-hand or in a left-hand position, as desired.

In the drawings I have illustrated my in- 30 vention as applied to a form of door-closing apparatus now in general use, which form I have shown only for purposes of illustration, inasmuch as my invention may be equally well applied to other forms of door-closing 35 apparatus.

In the drawings, Figure 1 shows in perspective the interior arrangement of such lock with my invention embodied therein. Fig. 2 is a view in detail of the levers of said lock. 40 Fig. 3 is a view in perspective of the interior of a modified form of such lock, and Fig. 4 shows in detail the lever of such modification.

A is a plate suitably hinged, as at A', to a base or casing B. The plate A has one portion C' that projects beyond the end of the plate. The base B is fastened to the jambs of a door in any suitable way, as by screws passing through the screw-holes B⁴. When 45 the lock is in position, the part C' projects 50 beyond the side of the door-jamb into the path of a sliding door that is hung on an in-

clined track and that is prevented from sliding into the closed position only by the projecting tongue C', which may, if desired, be integral with the plate A. Preferably C' is 55 the end of a bolt C, carried by the plate A and sliding thereon, as indicated in Fig. 1.

a is a slot in the plate, through which projects a stem c of the bolt C, and a handle c', by means of which the bolt may be moved 60 back and forth. The arch D is at once a bearing for the bolt C and a means by which the levers, hereinafter described, hold the plate A and its projection C' locked.

In Fig. 1 I have shown a double arrange- 65 ment of levers in the casing B for securing and releasing the plate A, as desired. E is an arm having at one end a hub E³, from both sides of which extend pivots E⁴ E⁴, which work in suitable sockets A³ and B³ in the plate and 70 in the casing. Near the other end of the arm E are corresponding projections E⁵ E⁵ on both sides of the arm, the outer one of which (shown square in Fig. 1) is merely a spacing member 75 to secure proper alinement of E in the casing. Near the same end of the arm both faces thereof are outwardly and inwardly beveled, as shown at E' E' and E² E², which said beveled surfaces are adapted to fit behind the beveled surfaces D' D' of the arch D when 80 the lock is closed. The end E⁶ of the arm is arranged to slide back and forth in an inclined groove E⁷, formed in the end of the casing B by the plate F, which groove limits the motion of the arm E. G is a link having 85 similar ends G' G', in which are sockets G³ G². H is another lever-arm having at one end a hub H³, from both sides of which pivots H⁴ H⁴ project, which work in sockets B² B² and A² A² in the base and plate, respectively. Near this 90 end of said arm are the double projections H² H². The curved upper end H' of this arm passes through an opening B' in the casing, and to it is fastened the thermal fuse-chain or other securing device L. The arms E and 95 H are joined by the link G, the projections E² and H² respectively fitting into the sockets G² G² on the opposite ends of the link. The arrangement is such that when the end H' of the lever H is raised by the chain L the bevelled part E' of the lever E is maintained in a 100 raised position, and if the plate A is closed

its beveled surface D' will be behind the surface E', and will thus be held securely locked and the plate A will be prevented from swinging open even under full pressure of the door 5 on the part C'. When the lever H is dropped, as by the breaking of the chain L, the lever E falls slightly, releasing the plate A and allowing the door to cause it to swing on its hinges and the door itself to close. The bearing-surfaces D' and E' need not always be beveled or inclined; but this is in most instances desirable as insuring the prompt unlocking of the plate. J J represent a guard removably fastened by a screw J² to a block J', preventing the lever-arms E and H from falling from the sockets in the base B when the plate A is swung open. It is to be noticed that the pairs of sockets A² A³ and B² B³ not only correspond to each other respectively, but that 15 each one is the same distance from the end and side of the plate or base. The same is true of the sockets A³ A⁴ and B³ B⁴. The levers E and H are made reversible, each pivot, projection, and bearing in use when the levers are in the position shown in the drawings being so arranged that said levers may be reversed and used on the opposite side of said lock. Each bearing of the plate A and 20 of the casing B that comes in contact with the levers is in duplicate and arranged to operate with the levers when reversed. The opening B' is also in duplicate to permit the passage of the lever-arm H' in either position, and the groove E' is similarly arranged in respect to the end E⁶ of the lever E. Thus it 25 is evident that the levers E and H may be reversed and the lock be made to serve either as a right-hand or a left-hand lock, as desired. This feature is of great importance in an apparatus of this sort.

In Figs. 3 and 4 I have shown a simple form of reversible lock in which only one lever is used. The plate A and its parts are the same as in Fig. 2 except that only one 30 socket A⁴ need now be used, and the casing B is the same as before except that only one socket B⁴ need be used and that the chain-holes B⁵ B⁶ are slightly different in location. K is the single reversible lever, having hub 35 K', duplicate pivots K² K³, and duplicate bearings E' E² E³, as before. k k are eyes on opposite sides of the lever K, to which may be attached the chain L. This lever 40 may thus be used on either side of the bearing of the hinged plate, and the lock thus reversed.

It is evident that instead of the casing and plate-carrying sockets for pivots on the levers the levers may be provided with sockets into 45 which fit projections carried by the plate and casing.

While I have shown my invention as applied to a fire-door lock having a plate of peculiar shape hinged to a base of special 50 construction, I do not intend to limit myself to this embodiment. My invention is equally present in any locks of this sort having a

removable bar, preferably a pivoted or hinged plate or bolt, carried on any base, said plate or bolt being successively secured and released by one or more levers controlled by a thermal chain or equivalent means, and said lever or levers and their bearings on the base and on the plate or bolt being reversible, so that the lock may readily be changed from a 75 right-hand to a left-hand lock, and vice versa. Many ways of embodying my invention will be apparent to those skilled in this art.

Having thus described my invention, what I claim as new, and desire to secure by Letters 80 Patent, is—

1. In a door-closing apparatus, a bar adapted to extend across the line of travel of the door, a locking device to hold said bar in position, a support upon which said bar and 85 said locking device are movably mounted, duplicate bearings on said support upon either of which said locking device may be mounted, the coacting surfaces of said locking device and of said bar being reversible. 90

2. In a door-closing apparatus, a manually-movable bar adapted to extend across the line of travel of a door, a guiding-piece in which said bar is movably mounted, a locking device to hold said guiding-piece in position, a support upon which said locking device and said guiding-piece are movably mounted, duplicate bearings upon said support for said locking device, the engaging 95 surfaces of the locking device and of the 100 guiding-piece where the two coact being reversible.

3. In a door-closing apparatus, a movable bar adapted to extend across the line of travel of a door, a base-plate for securing said bar 105 to a door-jamb, a locking device for holding said bar in position and duplicate bearings for said locking device formed on said base-plate, said locking device being reversible.

4. In a door-closing apparatus, hinged door-retaining means, a locking device to hold said retaining means in position, securing means adapted to secure said retaining means to a door-jamb, means for supporting and releasing the locking device, duplicate bearings 115 formed on said securing means for said locking device, said locking device and said retaining means and the engaging surfaces of said retaining means and said locking device being reversible. 120

5. In a door-closing apparatus, hinged door-retaining means, a base for said retaining means, a lever, means for maintaining said lever in engagement with said retaining means and for releasing it therefrom, duplicate bearings on said retaining means for 125 said lever, said lever and the engaging surfaces of said lever and said retaining means being reversible.

6. In a door-closing apparatus, a hinged plate, a sliding bolt carried thereon, a base to which said plate is hinged, a lever, means for maintaining said lever in engagement with said plate and for releasing it therefrom,

- duplicate bearings formed in said plate for said lever and for the means for maintaining said lever in engagement with said plate, said lever and said maintaining means, and 5 the coacting surfaces of said lever and plate being reversible.
7. In a door-closing apparatus, a hinged plate carrying a sliding bolt, a base to which said plate is hinged, a locking device for said 10 plate, means for retaining the locking device, duplicate bearings formed in the base for said locking device, said locking device and retaining means and the coacting surfaces of said locking device and said plate being reversible.
8. In a door-closing apparatus, a hinged plate carrying a sliding bolt, a base to which said plate is hinged, a lever removably pivoted in said base and engaging said plate 20 when raised and releasing the same when lowered, said lever being reversible and said lever, base and plate being provided with duplicate coacting bearings, and means for supporting and operating said lever, as and for the purposes aforesaid.
9. In a door-closing apparatus, a hinged plate carrying a sliding bolt, a base to which said plate is hinged, a lever removably pivoted in said base and engaging said plate 30 when raised, and releasing the same when lowered, said lever being reversible, and said lever and base being provided with duplicate coacting bearings, and means for supporting and operating said lever, as and for the purposes aforesaid.
10. In a door-closing apparatus, a hinged plate carrying a sliding bolt, a base to which said plate is hinged, levers removably pivoted to said base and loosely connected with 40 a reversible link, one of said levers engaging said plate when raised and releasing the same when lowered, said levers and link being provided with reversible bearings for said parts and for said base and plate, and means for supporting and operating said levers, as and for the purposes aforesaid.
11. In a door-closing apparatus, a casing having duplicate and corresponding openings in the top and bottom faces, a front plate 50 hinged to said casing and carrying a sliding bolt, said plate having a double-ended catch, a lever pivoted to said casing and having reversible surfaces engaging with either end of said catch, and means for supporting and operating said lever, as and for the purposes aforesaid.
12. In a door-closing apparatus, a casing having duplicate and corresponding openings in the top and bottom faces, a front plate 60 hinged to said casing and carrying a sliding bolt, said plate having a double-ended catch, a system of reversible levers pivoted to said casing and to said plate and having surfaces adapted to engage either end of said catch, said levers and the bearings of the same on 65 the casing and plate and on the catch being reversible, and means for supporting and operating said levers, as and for the purposes aforesaid.
13. In a door-closing apparatus, a casing 70 having duplicate and corresponding openings in the top and bottom faces, a front plate hinged to said casing and carrying a sliding bolt, said plate having a double-ended catch, a lever pivoted to said casing and having reversible surfaces engaging with either end of said catch, and means for supporting and operating said lever, and a guard-piece for said lever, as and for the purposes aforesaid.
14. In a door-closing apparatus, a hinged 75 plate carrying a sliding bolt, a base to which said plate is hinged, a locking device for said plate, means for retaining the locking device in position, duplicate bearings formed in the base for said locking device, said locking device and retaining means and the coacting surfaces of said locking device and said plate being reversible and the coacting surfaces of said locking device and said plate being beveled.
15. In a door-closing apparatus, hinged door-retaining means, a base for said retaining means, a lever, means for maintaining said lever in engagement with said retaining means and for releasing it therefrom, duplicate bearings on said retaining means for said lever, said lever and the engaging surfaces of said lever and said retaining means being reversible and said engaging surfaces being beveled to permit the ready disengagement 90 of said lever and said retaining means.
16. In a door-closing apparatus, a bar adapted to extend across the line of travel of the door, a locking device having a beveled portion to hold said bar in position, a support 105 upon which said bar and said locking device are movably mounted, duplicate bearings on said support upon either of which said locking device may be mounted, the coacting surfaces of said locking device and of said bar 110 being reversible.
17. In a door-closing apparatus, a casing having duplicate and corresponding openings in the top and bottom faces, a front plate 115 hinged to said casing and carrying a sliding bolt, said plate having a double-ended beveled catch, a lever pivoted to said casing and having reversible, beveled surfaces engaging with either end of said catch, and means for supporting and operating said lever, as and for the purposes aforesaid.
